DESIGN FOR A TABLE

Willard H. Bond, Jr., East Grand Rapids, Mich.,
assignor to American Seating Company, Grand Rapids, Mich., a corporation of New Jersey

Application March 29, 1937, Serial No. 68,461

Term of patent 14 years

To whom it may concern:

Be it known that I, Willard H. Bond, Jr., a citizen of the United States, residing at East Grand Rapids, in the county of Kent and State of Michigan, have invented a new, original, and ornamental Design for a Table, of which the following is a specification, reference being had to the accompanying drawing, forming a part thereof, in which:

The distinguishing, essential and dominant features or characteristics of the design reside in the table top with its rounded marginal widths, lengths and corners, and its cross-sectionally elliptical legs and the depending sides and ends of the table top which are provided with projecting longitudinal medial portions whose opposite ends are curved inwardly as shown in full lines.

I claim:

The ornamental design for a table as shown and described.
